GOOGLES

Emil B. Meyrowitz, New York, N. Y., and John Louis Wagner, Union City, N. J., assignors to E. B. Meyrowitz, Inc., a corporation of New York

Application April 24, 1931. Serial No. 532,400

7 Claims. (Cl. 2—14)

This invention relates to goggles and in particular to that type of goggles which are especially serviceable in aviation and other uses. In certain particulars, the invention is especially suitable for goggles having eyecups which are split transversely at one point and flexed in their own plane to opened and closed positions to release and secure the lens. One object of the invention is to provide an improved locking means 10 at the transverse split in the eyecup which locking means is reliable and which is easily and readily operated either to open or close the eyecups. Another object is to provide a locking means which may be securely fastened in the 15 locked position, the head band attachment being enlisted for this purpose. A further object is to provide an improved arrangement for detachably securing the cushion to the eyecup.

In accordance with this invention, the locking structure for the eyecup which is split transversely at one point includes a locking member which is rotatably mounted on the eyecup at one side of the transverse split therein. The locking member extends laterally from the eyecup, and 25 at its base, it is oblong in cross section. At the other side of the split in the eyecup, there is pivotally secured to the eyecup a link which is of sufficient length to overlap the split in the eyecup and the locking member. The link is 30 provided with a slot which is of sufficient width and length to receive the locking member when the locking member is positioned with its major transverse axis parallel to the longitudinal axis of the slot. The major transverse axis of the 35 locking member is longer than the width of the slot so that if, after the locking member has passed through the slot in the link, it is rotated, the link will be securely locked in place.

Another phase of our invention relates to the 40 bridge of the goggle. The bridge is constructed in two parts, each part forming a portion of the cross piece and one leg of the bridge. One of the parts constitutes a shank, and the other part has a chuck formed thereon which is adapted to 45 receive and clamp the shank of the other part. The two parts are separable and by virtue of the construction, the bridge is adjustable to vary the distance between the eyecups. The 50 chuck comprises a plurality of jaws which are tapered on their outer surface. The jaws are pressed into clamping position by an internally threaded sleeve which fits over the jaws. A stop shoulder is provided on the chuck which 55 limits the movement of this internally threaded sleeve. By providing this stop shoulder, the di-

rection in which the sleeve must be turned to open or close the chuck is definitely determined, and the stop shoulder eliminates the possibility of straining the clutch by limiting the movement of the sleeve.

The invention also contemplates an improved construction and arrangement for attaching the cushion to the eyecup. The eyecup tapers inwardly, and the cushion is provided with an outwardly extending lip which has a taper complementary to the taper of the eyecup. A sheet metal reinforcing band engages the inner circumferential surface of the tapered lip of the cushion, and the outer circumferential surface of the lip of the cushion is engaged by the inner 60 circumferential surface of the eyecup. By closing the eyecup over the lip of the cushion, the cushion is firmly secured with respect to the eyecup.

A feature of the invention is contained in the 65 arrangement and construction of the eyecup for connecting the eyecup to the bridge member. The eyecup is provided with a bearing socket adapted to receive the leg of the bridge member. The inner wall of the bearing socket has formed 70 therein communicating circumferential and longitudinal grooves to receive a pin extending from the leg of the bridge which cooperates with the circumferential groove to hold the leg in the bearing socket. The circumferential groove 75 terminates at one end at the side of the longitudinal groove so that if the eyecup is turned about the leg of the bridge until the pin reaches the end of the circumferential groove, it will be 80 in alignment with the longitudinal groove and 85 the leg of the bridge may be withdrawn from the bearing socket.

Other objects and advantages of our invention 90 will be apparent from the following particular description of the embodiment illustrated in the 95 drawing in which:

Fig. 1 is a front elevation of a pair of goggles constructed in accordance with my invention;

Fig. 2 is a plan of the same;

Fig. 3 is an enlarged fragmentary section illustrating the bridge member and its connection to the eyecup;

Fig. 4 is an enlarged fragmentary plan partly in section taken on the line 4—4 of Fig. 3, and showing the bearing socket in the eyecup for the 105 leg of the bridge member;

Fig. 5 is an enlarged fragmentary end elevation;

Fig. 6 is an enlarged fragmentary sectional elevation;

Fig. 7 is an enlarged fragmentary sectional plan taken on the line 7—7 of Fig. 6; and

Fig. 8 is an enlarged fragmentary section of an eyecup taken on the line 8—8 of Fig. 1.

5 In the goggles shown in the drawing, the eyecups 1 are connected together by a bridge member and are identical with the exception that they are relatively reversed. Each eyecup is split transversely at the temple end and a locking means is provided at the split. The locking means provided is the same for each eyecup and includes a link 2 which is pivotally secured to the eyecup. The link is curved to correspond with that portion of the eyecup over which it is adapted to lie. At one end of the link, there is formed a hinge 3 which is pivoted to a lug 4 formed on a plate 5 which is secured to the inner surface of the eyecup, the lug extending through the eyecup. The link is shaped to fit snugly against the outer surface of the eyecup and it is provided with an overlapping portion 6 which overlaps the bezel of the eyecup, and when the eyecup is closed, the link overlies the transverse split therein.

10 25 On the eyecup at one side of the split therein, opposite to that to which the link is pivoted, there is formed an elevated portion 7. Through this elevated portion of the eyecup a pin 8 extends, the pin 8 extending laterally from the outer surface of the eyecup and being secured to the eyecup. On the pin, there is rotatably mounted a locking member 9 which is frusto-conical in shape having diametrically opposed surfaces planed to form a pair of parallel sides 10, making the base of the locking member oblong in cross section. The locking member is secured in place on the pin 8 by a cap 11 formed on the top of the pin and overhanging the end of the locking member. The distance between the parallel sides of the locking member is equal to the width of the extension 7 formed on the eyecup and from which the locking member extends.

15 40 The link 2 has a slot 12 formed therethrough. The slot 12 is of sufficient width and length to receive the extension 7 formed on the eyecup, and to receive the locking member 9 when the locking member is positioned with its major transverse axis, or the parallel sides thereof, parallel to the longitudinal axis of the slot. The slot is of less width, however, than the major axis of the locking member. When the locking member is positioned with the major axis parallel to the longitudinal axis of the slot and the eyecup is held in the closed position, the link 55 may be swung about its hinge connection to the eyecup to lie against the eyecup, the locking member passing through the slot in the hinge. When the hinge is in the closed position and the locking member is rotated about the pin so that this major axis is transverse to the longitudinal axis of the slot, the link is securely locked in the closed position.

65 70 To prevent accidental opening of the eyecup during service, the pin extending from the extension 7 on the eyecup is provided with a transverse hole 13. The locking member is also provided with a transverse hole 14 which passes through the parallel sides of the locking member. The transverse hole 13 through the pin lies in the plane including the longitudinal axis of the slot formed through the link 2. When the locking member is turned so that its major transverse axis is perpendicular to the longitudinal axis of the slot, in which position the link is locked over the extension 7 on the eyecup, the hole 13 through

the pin and the hole 14 through the locking member are in alignment, and the attachment for the head band may pass through these holes thereby securing the head band to the goggle and at the same time, securing the locking member in the locked position.

80 85 The eyecups are formed from sheet metal so that they can flex in their own plane. As clearly shown in Fig. 8, the eyecups taper inwardly from the bezel thereof. For each eyecup, there is provided a cushion 15. Each cushion has an outwardly extending lip 16 which is adapted to extend into the eyecup. The outwardly extending lip of the cushion is also tapered, the taper of the lip being complementary to the taper of the eyecup. Secured to the inner circumferential surface of the lip of the cushion, there is a flexible sheet metal reinforcing band 17. When in position in the eyecup, and the eyecup is closed over the lip of the cushion, the inner circumferential surface of the eyecup engages the outer circumferential surface of the lip of the cushion. The reinforcing band 17 prevents the lip of the cushion from flexing within the eyecup, and the taper of the eyecup and the lip of the cushion 90 prevent relative movement of the eyecup and cushion in a direction to withdraw the lip of the cushion from the eyecup. The cushion abutting against the edge of the eyecup serves to prevent outward axial movement of the cushion. 95 By opening the eyecup and flexing the eyecup in its own plane, the cushion may be readily removed and replaced.

100 105 The two eyecups are united by a bridge member which is constructed in two parts. Each part of the bridge member forms a part of the cross-piece and one leg 18 thereof. One of the parts has a chuck formed thereon which includes a plurality of jaws 19. The jaws are tapered longitudinally and are threaded on their 110 outer surfaces. The threads on the outer surface of the jaws of the chuck are engaged by an internally threaded cup-shaped sleeve 20. As the sleeve is threaded on to the jaws, the taper of the jaws causes the jaws to be moved towards the 115 axial center of the chuck and as the sleeve is moved in the opposite direction the jaws return to their original position under their own resiliency. At the end of the jaws, there is a shoulder 120 125 formed on the bridge member. This shoulder acts as a stop shoulder to limit the movement of the sleeve. In limiting the movement of the sleeve, the shoulder also determines the direction which the sleeve must be turned in order to loosen or tighten the chuck. Thus, when the sleeve 130 is abutting against the shoulder, the chuck is in its clamping position and exerting its maximum clamping effect. To loosen the chuck, the sleeve must be rotated so that the coaction of the threads will be to move the sleeve away from 135 the shoulder.

140 145 The chuck is adapted to clamp that portion 22 of the other part of the bridge member which forms part of the cross-piece thereof and which constitutes a shank. When the chuck is loosened, the shank may be inserted between the jaws of the chuck through an opening in the end of the sleeve 20 and when the sleeve is tightened on the jaws, the shank is firmly clamped between the jaws. It is obvious that the shank may be inserted in the chuck to a lesser or greater distance depending upon the desired distance between the eyecups.

150 The bridge member is secured to the eyecups through the legs 18 thereof which are received

in bearing sockets 23 secured to and extending into the eyecups. Each bearing socket is provided with an arm 24 which is riveted to the outer circumferential surface of the eyecup. Each of 5 the legs of the bridge member is bifurcated at its end to form a resilient end section. These resilient end sections are provided with a shoulder 25 which, when the leg is in position in the bearing socket, is adapted to engage the end of the 10 bearing socket. The leg is also provided with an integral collar 26 which is adapted to abut against the upper end of the bearing socket to limit the inward movement of the leg. Intermediate the 15 end of the leg of the bridge, there is a pin 27 extending laterally from the surface of the leg. The inner wall of the bearing socket is provided with communicating longitudinal and circumferential slots 28 and 29 which are adapted to receive the pin 27. The circumferential slot 29 20 terminates at one end in alignment with the side wall of the longitudinal slot 28. With this construction, when it is desired to remove the eyecup from the bridge member, the pin may be aligned with the longitudinal slot by rotating the eyecup 25 with respect to the leg of the bridge member until the pin abuts against the end of the circumferential slot, in which position it will be in alignment with the longitudinal slot. The end of the leg member may then be pressed so as to release 30 the shoulder 25 from the lower edge of the bearing socket and the leg may be withdrawn from the bearing socket.

It is obvious that various changes may be made in the details of the embodiment illustrated in the 35 drawing and above particularly described within the principle and scope of our invention as expressed in the appended claims.

We claim:

1. As a frame member for goggles, an eyecup 40 split transversely thereof for expanding the eyecup, and locking means at the transverse split in the eyecup comprising a locking member rotatably mounted on the eyecup at one side of the split therein, said locking member being oblong 45 in cross section at the base thereof, and a link pivotally secured to the eyecup on the other side of the transverse split, said link being adapted to overlie the split in the eyecup and having a slot of sufficient width and length to receive the lock 50 member when the locking member is positioned with its major transverse axis parallel to the longitudinal axis of the slot.

2. As a frame member for goggles, an eyecup 55 split transversely thereof for expanding the eyecup, and locking means at the transverse split comprising a locking member rotatably mounted on the eyecup, said locking member being frustoconical and having diametrically opposite surfaces planed to form an oblong base, and a link 60 pivotally secured to the eyecup on the other side of the transverse split, said link being adapted to overlie the split in the eyecup and having a slot of sufficient width and length to receive the lock 65 member when the lock member is positioned with the planed surfaces parallel to the longitudinal axis of the slot.

3. As a frame member for goggles, an eyecup 70 split transversely thereof for expanding the eye-

cup, and locking means at the transverse split in the eyecup comprising a link having a slot therethrough pivotally secured to the eyecup at one side of the transverse split and adapted to overlie the split in the eyecup, an elevated portion 80 formed on the eyecup on the other side of the split of such dimensions as to be received in the slot in the link, and a locking member rotatably mounted on said elevated portion, said locking member being oblong in cross section at the base and adapted to pass through the slot in the link when positioned with its major transverse axis parallel to the longitudinal axis of the slot.

4. As a frame member for goggles, an eyecup 85 split transversely thereof for expanding the eyecup, and locking means at the transverse split in the eyecup comprising a link having a slot therethrough pivotally secured to the eyecup at one side of the transverse split and adapted to overlie the split in the eyecup, an elevated portion 90 formed on the eyecup on the other side of the split of such dimensions as to be received in the slot in the link, a pin extending from said elevated portion and secured thereto, and a locking member rotatably mounted on said pin, said locking member 95 being frusto-conical and having a pair of diametrically opposite planes, parallel surfaces forming an oblong base and adapted to pass through the slot in the link when positioned with the parallel surfaces thereof parallel to the longitudinal axis of the slot.

5. As a frame member for goggles, an eyecup 100 split transversely thereof for expanding the eyecup, and locking means at the transverse split in the eyecup comprising a link having a slot therethrough pivotally secured to the eyecup at one side of the transverse split and adapted to overlie the split in the eyecup, an elevated portion 105 formed on the eyecup on the other side of the split of such dimensions as to be received in the slot in the link, a pin having an opening therethrough extending from said elevated portion and secured thereto, and a locking member rotatably mounted on said pin having an opening 110 therethrough adapted to be aligned with said opening in said pin when in the locked position, said locking member being oblong in cross section at the base and adapted to pass through the slot in the link when positioned with its major transverse axis parallel to the longitudinal axis of the slot.

6. A goggle frame comprising an eyecup having a bearing socket for the leg of a bridge, the wall of said bearing socket having communicating longitudinal and circumferential slots, said circumferential slot terminating at one end in alignment with the longitudinal slot.

7. In a goggle, in combination an eyecup having a bearing socket, a bridge having a leg member adapted to be received in the bearing socket of the eyecup, and a pin extending laterally from 135 the leg member of the bridge, the walls of said bearing socket having communicating longitudinal and circumferential slots to receive said pin, and the circumferential slot terminating at one end in alignment with the longitudinal slot.
